Inventor:
John Jacob Kaufmann,
By Jas. C. Hobbs with
Attorney.

UNITED STATES PATENT OFFICE.

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE FRAME.

Application filed November 18, 1927. Serial No. 234,058.

My invention relates to heddle frames for looms, and it relates more particularly to improved means, in a heddle frame of the usual type, for supporting the heddle bars intermediate their ends.

The principal object of my present invention is to provide in a heddle frame improved means for supporting the heddle bars intermediate their ends, which will securely support said bars against undesirable motion and displacement, but which, however, will permit the bars to be quickly and conveniently mounted in and dismounted from the frame when desired.

15 My present invention contemplates an improved form of supporting device in the use of which possibility of the warp controlled by adjacent frames in the loom fouling on the supporting devices will be reduced to a minimum, thereby permitting the greatest possible separation of the warp in the formation of the shed.

20 My present invention further contemplates a supporting device which may be readily adjusted with respect to the top and bottom rails of the frame, so that the heddle supporting bars will be properly positioned and the heddles will not bind on the supporting bars, or on the other hand be permitted too great an up and down movement thereon.

25 My present invention further contemplates an improved form of supporting device which may be inexpensively constructed, and in which there will be little likelihood of the parts becoming disarranged or damaged in use.

30 The nature and characteristic features of my invention will be more readily understood from the following description, taken 40 in connection with the accompanying drawings forming part hereof, in which

35 Figure 1 is an elevational view of a heddle frame provided with heddle bar supporting devices embodying the main features of my present invention;

45 Fig. 2 is a fragmentary detail thereof, enlarged;

50 Fig. 3 is a sectional view taken approximately on the line 3—3 of Fig. 2, the parts being shown in the normal positions assumed while supporting the heddle bar;

55 Fig. 4 is a similar view, but with the parts

in the open position for the purpose of removing the heddle bars therefrom or mounting the same thereon; and

Fig. 5 is a perspective view of the supporting device detached from the rail of the heddle frame.

60 Referring to the drawings, the heddle frame there shown comprises top and bottom rails 10, connected at their ends by means of side strips 11. Extending from end to end of the heddle frame and arranged near the top and bottom rails 10, in the usual manner, are the heddle supporting bars 12, 65 on which the heddles 13 are mounted, also in the usual manner.

65 The devices comprising the novel portion of the present invention are located at suitable locations on the inner edges of the top and bottom rails 10. Each of these devices as shown in the drawings includes a bolt member 20, having a shank 21, the end of which is threaded as at 22 in the manner similar to an ordinary wood screw, with the exception that the same is not tapered for the greater portion of its length.

70 The bolt member 20 is also provided with a head portion 23, preferably made by flattening and spreading the material of the rod 75 from which the bolt member is formed. In the head portion of the bolt member there is provided a recess 24, in which the heddle bar 12 is adapted to be seated.

75 At the end of the recess 24, toward the free end of the head portion, there is provided a lip 25 which assists in properly positioning the heddle bar 12 within the recess 24, and also serves to engage and retain the marginal edge of the heddle bar when the same is locked within said recess 24 in the manner to be hereinafter explained.

80 Mounted on the head portion of the bolt member 20 is a slide member 30. The slide member 30 is provided at one end with a longitudinal slot 31. The other end of the slide member 30 is bent over as at 33, and the bent over portion 33 is provided with an aperture 34, through which the shank portion 21 of the bolt member 20 extends. In 85 this manner, one end of the slide member 30 is properly positioned with respect to the head portion 23 of the bolt 20. The other end of the slide member 30, which is provided

with the slot 31, is positioned with respect to the head portion 23 of the bolt 20 by means of a rivet 36, which extends through a portion of the slot 31. The rivet 36 is secured in the head portion 23 of the bolt member 20 between the recess 24 and the shank portion 21.

The portion of the slide member 30 adjacent the bent over portion 33 thereof, is disposed out of the main plane of the slide member, as at 35, to clear the shank portion of the bolt 20 and also to afford a larger seat upon the bent over portion 33 of the slide member.

15 A coil spring 40 surrounds the smooth or unthreaded portion of the shank 21 of the bolt 20. Said coil spring bears at one end against the bent over portion 33 of the slide member 30, and at its other end is seated in 20 a recess 41 provided in the inner edge of the rail 10 of the heddle frame proper. If desired, a washer 42 may be interposed between the end of the coil spring 40 and the bent over portion 33 of the slide member 30.

25 The spring 40 normally tends to cause the slide member 30 to occupy a position as shown in Fig. 3 of the drawings, whereby the heddle bar 12 will be engaged by the slot 31 of the slide member 30, and normally will be retained thereby in position within the recess 24 of the head portion 23 of the bolt 20. It will here be noted that the heddle bar will be engaged at one marginal portion by the slotted slide member 30, and at the other marginal portion will be retained against coming out of the recess 24 by the lip 25 provided at the other end of said recess.

The movement of the slide member under the tension of the spring 40 is limited by the 40 engagement of the inner end of the slot 31 with the rivet 36, the head of which rivet, as hereinbefore pointed out, serves to guide the slotted end of the slide member 30 with respect to the recessed head portion 23 of the bolt 20.

45 The operation of the device may now be readily understood. The supporting devices being mounted in the heddle frames at desired locations upon the inner edges of the 50 top and bottom rails 10 thereof, and the heddle bars with the heddles mounted thereon being placed in the frame in the usual manner, with the ends thereof secured in position in the side strips 11 of the frame by fastening devices of any preferred type, the slide member 30 is then manually pushed to the 55 open position as shown in Fig. 4 of the drawings, the projecting part of the bent over portion 33 affording a convenient finger piece 60 for the manipulation of the slide member.

The heddle bar 12 is now inserted in the recess 24 provided in the head portion 23 of the bolt 20, and when properly positioned therein, the slide member 30 is released and permitted to return to the normal locking posi-

tion as shown in Fig. 3 of the drawings, being thereafter maintained in such position by the coil spring 40.

The slot 31 of the slide member 30 will now serve to retain the heddle bar 12 within 70 the recess 24 of the head portion 23 of the bolt 20, and will securely hold the same against displacement during the operation of the loom.

When it is desired to remove the heddle 75 supporting bar from the supporting device, it will be necessary merely to again push and hold the slide member 30 in the position shown in Fig. 4 of the drawings, and the heddle bar 12 may then be readily disengaged from the supporting device.

Should it be found at any time that the heddle supporting bars 12 are so located that undue tension is placed upon the heddles whereby the same will bind upon the heddle 85 supporting bars, or on the other hand, should it be found that the heddle bars are so positioned that the heddles are permitted too much up and down movement in the frame, the proper adjustment of the device for supporting the heddle bars may be easily made by first removing the heddle bar from the 90 supporting device, and then threading the bolt in or out with respect to the rail 10 in which it is mounted until the recess 24 of the 95 head portion 23 of the bolt member 20 is properly located.

It will be seen that with devices constructed as hereinbefore described, the heddle bars will be fixedly supported intermediate their 100 ends, whereby undue lateral movement of the same will be effectively prevented, and that adjustment of the supporting device with respect to the top and bottom rails may be quickly and conveniently made, so that the 105 heddle bars may at all times be properly positioned. It will also be apparent that the adjustment of the supporting devices when made will be maintained by reason of the bolt members being prevented from turning on 110 account of the engagement of the heddle bars by the slotted portions of the slide members.

It will also be noted that with a supporting device constructed as hereinbefore described, there is a very minimum of projecting parts beyond the inner margin of the heddle supporting bar, and also that there are no rivets or other protuberances beyond the inner margin of the heddle bar, upon which the warp controlled by adjacent frames in the 115 loom might foul in the shedding.

Having thus described the nature and characteristic features of my invention, what I claim as new and desire to secure by Letters Patent, is:

1. In a heddle frame, the means for supporting the heddle bars intermediate their ends, comprising a member carried by the heddle frame rail, said member having a flat portion provided with a recess adapted to re- 120

ceive and support the heddle bar, a member slidably mounted on said first mentioned member having a portion provided with a slot extending to the end thereof and adapted to engage the heddle bar and lock the same in the recess, and a rivet passing through the slot in the slidable member and secured to the flat portion of the other member.

2. In a heddle frame, the means for supporting the heddle bars intermediate their ends, comprising a member adjustably carried by the heddle frame rail, said member having a flat portion provided with a recess adapted to receive and support the heddle bar, a member slidably mounted on said first mentioned member having a portion provided with a slot extending to the end thereof and adapted to engage the heddle bar and lock the same in the recess, and a rivet passing through the slot in the slidable member and secured to the flat portion of the other member.

3. In a heddle frame, the means for supporting the heddle bars intermediate their ends, comprising a member adjustably carried by the heddle frame rail, said member having a flat portion provided with a recess adapted to receive and support the heddle bar, a lip provided at one end of the recess adapted to assist in retaining the heddle bar in the recess, a member slidably mounted on said first mentioned member having a portion provided with a slot extending to the end thereof and adapted to engage the heddle bar and lock the same in the recess, and a rivet passing through the slot in the slidable member and secured to the flat portion of the other member.

4. In a heddle frame, the means for supporting the heddle bars intermediate their ends, comprising a member adjustably carried by the heddle frame rail, said member having a flat portion provided with a recess adapted to receive and support the heddle bar, a member slidably mounted on said first mentioned member having a portion provided with a slot extending to the end thereof and adapted to engage the heddle bar and lock the same in the recess, a rivet passing through the slot in the slidable member and secured to the flat portion of the other member, and a spring adapted to impel said slidable member to the locking position.

5. In a heddle frame, the means for supporting the heddle bars intermediate their ends, comprising a member adjustably carried by the heddle frame rail, said member having a flattened portion provided with a recess adapted to receive and support the heddle bar, a member slidably mounted on said first mentioned member having a portion provided with a slot extending to the end thereof and adapted to engage the heddle bar and lock the same in the recess, a rivet passing through the slot in the slidable mem-

ber and secured to the flat portion of the other member, and a spring adapted to impel said slidable member to the locking position, said spring bearing at one end against a portion of the slidable member and seated at the other end in a recess in the heddle frame rail. 70

6. In a heddle frame, the means for supporting the heddle bars intermediate their ends, comprising a member adjustably carried by the heddle frame rail, said member having a flat portion provided with a recess adapted to receive and support the heddle bar, a lip provided at one end of the recess adapted to assist in retaining the heddle bar in the recess, a member slidably mounted on said first mentioned member having a portion provided with a slot extending to the end thereof and adapted to engage the heddle bar and lock the same in the recess, a rivet passing through the slot in the slidable member and secured to the flat portion of the other member, and a spring adapted to impel said slidable member to the locking position, said spring bearing at one end against a portion of the slidable member and seated at the other end in a recess in the heddle frame rail. 80

7. In a heddle frame, the means for supporting the heddle bars intermediate their ends, comprising a bolt member threaded directly in the heddle frame rail, said bolt member having a flattened head portion provided with a recess adapted to receive and support the heddle bar, a member slidably mounted on said bolt having a portion adjacent the recess provided with a slot extending to the end thereof and adapted to engage the heddle bar and lock the same in the recess, the other end of the slidable member being bent over and provided with an aperture in said bent over portion through which the shank of the bolt passes, and a rivet passing through the slot in the slidable member and secured to the head portion of the bolt between the recess and the shank portion. 100

8. In a heddle frame, the means for supporting the heddle bars intermediate their ends, comprising a bolt member threaded directly in the heddle frame rail, said bolt member having a flattened head portion provided with a recess adapted to receive and support the heddle bar, a lip provided at one end of the recess adapted to assist in retaining the heddle bar in the recess, a member slidably mounted on said bolt having a portion adjacent the recess provided with a slot extending to the end thereof and adapted to engage the heddle bar and lock the same in the recess, the other end of the slidable member being bent over and provided with an aperture in said bent over portion through which the shank of the bolt passes, and a rivet passing through the slot in the slidable member and secured to the head portion of the bolt between the recess and the shank portion. 115

9. In a heddle frame, the means for sup-

- porting the heddle bars intermediate their ends, comprising a bolt member threaded directly in the heddle frame rail, said bolt member having a flattened head portion provided with a recess adapted to receive and support the heddle bar, a member slidably mounted on said bolt having a portion adjacent the recess provided with a slot extending to the end thereof and adapted to engage the heddle bar and lock the same in the recess, the other end of the slidable member being bent over and provided with an aperture in said bent over portion through which the shank of the bolt passes, a rivet passing through the slot in the slidable member and secured to the head portion of the bolt between the recess and the shank portion, and a spring adapted to impel said slidable member to the locking position. 5
- 10 10. In a heddle frame, the means for supporting the heddle bars intermediate their ends, comprising a bolt member threaded directly in the heddle frame rail, said bolt member having a flattened head portion provided with a recess adapted to receive and support the heddle bar, a lip provided at one end of the recess adapted to assist in retaining the heddle bar in the recess, a member slidably mounted on said bolt having a portion adjacent the recess provided with a slot extending to the end thereof and adapted to engage the heddle bar and lock the same in the recess, the other end of the slidable member being bent over and provided with an aperture in said bent over portion through which the shank of the bolt passes, a rivet passing through the slot in the slidable member and secured to the head portion of the bolt between the recess and the shank portion, and a spring adapted to impel said slidable member to the locking position. 15
- 15 15. In the slidable member and secured to the head portion of the bolt between the recess and the shank portion, and a spring adapted to impel said slidable member to the locking position. 20
- 20 10. In a heddle frame, the means for supporting the heddle bars intermediate their ends, comprising a bolt member threaded directly in the heddle frame rail, said bolt member having a flattened head portion provided with a recess adapted to receive and support the heddle bar, a lip provided at one end of the recess adapted to assist in retaining the heddle bar in the recess, a member slidably mounted on said bolt having a portion adjacent the recess provided with a slot extending to the end thereof and adapted to engage the heddle bar and lock the same in the recess, the other end of the slidable member being bent over and provided with an aperture in said bent over portion through which the shank of the bolt passes, a rivet passing through the slot in the slidable member and secured to the head portion of the bolt between the recess and the shank portion, and a coil spring adapted to impel said slid- 25 able member to the locking position, said spring being mounted on the shank of the bolt and bearing at one end against the bent over portion of the slidable member and seated at the other end in a recess in the hed- dle frame rail. 30
- 30 35. In the slidable member and secured to the head portion of the bolt between the recess and the shank portion, and a coil spring adapted to impel said slid- able member to the locking position, said spring being mounted on the shank of the bolt and bearing at one end against the bent over portion of the slidable member and seated at the other end in a recess in the hed- dle frame rail. 35

In testimony whereof, I have hereunto signed my name.

JOHN JACOB KAUFMANN.
